UNITED STATES PATENT OFFICE.

GIROLAMO SOLDANI, OF SPENCER, MASSACHUSETTS.

MILK-BOTTLE HOLDER.

Application filed August 18, 1922. Serial No. 582,761.

To all whom it may concern:

Be it known that GIROLAMO SOLDANI, a citizen of the United States of America, residing at Spencer, in the county of Worcester and State of Massachusetts, has invented new and useful Improvements in Milk-Bottle Holders, of which the following is a specification.

The object of the invention is to provide efficient means for receiving and holding a milk bottle or like receptacle on delivery by the vendor under conditions in which the same is protected from the attacks of bugs, cats and other animals which are likely to tamper with the same when deposited, as in the ordinary practice on the door or step or in the vestibule with consequent loss to the consumer by reason of the spilling or adulteration of the contents of the receptacle; and particularly to provide a device for the purpose indicated which may be constructed at a small cost and which when in position within convenient reach of the vendor is comparatively inconspicuous and not unsightly; and with these objects in view the invention consists in a construction and combination of parts of which a preferred embodiment is shown in the accompanying drawings, wherein:—

Figure 1 is a side view.

Figure 2 is a front view, and

Figure 3 is a rear view of a bottle holder constructed in accordance with the invention.

Figure 4 is a plan view of the blank from which the holder is formed.

The device consists essentially of a base or attaching plate 10 consisting of a strip of metal from the edges of which project the lateral arms 11 and 12 which are curved to form upper and lower clamps having yielding jaws of which the extremities are rolled or beaded to facilitate the forcing of a bottle such as that indicated at 13 into clamping relation therewith. At the lower end of the base or attaching plate there is arranged a platform 14 above which are disposed the guard wings 15 having terminal ears 16 which are adapted to underlap the platform and which may be secured thereto by rivets 17.

The base or attaching plate which may be secured by any suitable means to a wall,

post or other available support together with the arms 11 and 12, the platform 14 and the wings 15 which extend laterally from the base or attaching plate between the lower arms 12 and the platform, may be struck from a single sheet of metal or like material to form a blank as illustrated in Figure 4 and which may be then folded on the dotted lines indicated in said figure to occupy the relative positions indicated in Figures 1, 2 and 3. In the construction illustrated the base or attaching plate is provided with openings 18 for the reception of fastening screws or nails and the said plate is longitudinally beaded as indicated at 19 to afford the requisite stiffness thereto or to act as a reinforcement against bending.

The wings 15 when attached as described to the platform serve to support the latter in the horizontal position parallel with the clamps and the arms forming the upper clamp are preferably drawn together close to the plane of the base or attaching plate and secured by a transverse rivet 20 so that the upper clamp may be contracted sufficiently to snugly engage the neck of the bottle.

Having described the invention, what is claimed as new and useful is:—

A milk bottle holder consisting of a blank of sheet material in the form of an elongated strip having a base or attaching plate portion provided with a longitudinally disposed rib, upper and lower pairs of arms extending from the side edges of said strip at points between the ends of the rib, a platform formed by an extension of the lower end of the base or attaching plate portion, and lateral bracing wings extending from the side edges of the base or attaching plate portion near its lower end and provided with terminal ears secured to the platform at points below the lower arms, the arms of the upper pair being drawn together close to the plane of the base or attaching plate portion and secured together at a point above the lower arms to form a contracted clamp for the neck of a bottle.

In testimony whereof he affixes his signature.

GIROLAMO SOLDANI.
